WALTER G. PREDEY, OF SAN FRANCISCO, CALIFORNIA.

CARBON-FEEDING MECHANISM.

1,239,720.

Specification of Letters Patent. Patented Sept. 11, 1917.

Application filed May 29, 1916. Serial No. 100,684.

To all whom it may concern:

Be it known that I, WALTER G. PREDEY, a citizen of the United States, residing at San Francisco, in the county of San Francisco and State of California, have invented certain new and useful Improvements in Carbon-Feeding Mechanism, of which the following is a specification.

My present invention relates to new and useful improvements in electric carbon-feeding mechanism for arc-lamps, searchlights, electric reducing-furnaces, etc., and particularly to that class of carbon feeding mechanisms in which an electric motor is employed for moving the carbon points toward each other, to compensate for the combustion which takes place at the arc.

This invention has for its object primarily, to provide a carbon feeding mechanism of the above description which will prevent an abnormally high voltage across the arc when the same is burning. A further object is to increase the steadiness of the light, due to the uniformity of the feed movement. A still further object is to provide a means whereby the voltage across the arc can be adjusted without shutting down the motor which is running when the arc is in operation.

With these ends in view my invention consists in the details of construction and combination of elements hereinafter set forth, and then specifically designated by the claims. Its construction and operation will be described in detail, referring by numerals and letters to the accompanying drawings forming a part of this specification, and in which similar numerals and letters of reference designate corresponding parts in all figures.

In the accompanying drawings:—Figure 1, is a schematic view of an ordinary arc-lamp circuit equipped with my improved carbon-feeding mechanism. Fig. 2, is an enlarged detail side elevation of the periodic circuit closer 1 and centrifugal-contactor comprising parts 2, 3 and 4 as shown in Fig. 1. Fig. 3, is an enlarged side view of electro-magnet 12 and feeding mechanism 13 and 14 as shown in Fig. 1.

Referring to the drawings, A¹ and A² are line wires connecting to service wires through a compensator, transformer, rectifier or resistance, and supply current to the carbons. Motor circuit wires B¹ and B² are shown connecting motor 6 in multiple with line wires A¹ and A². The carbon feed controlling circuit C, C¹ and C² is a derived circuit in multiple with arc circuit A¹ and A² and motor circuit B¹ and B². A periodic circuit closer 1 is shown fixedly attached to the shaft 8 of motor 6. A brush 5 conducts current from line A² through wire C to periodic circuit closer 1. A segment 9 forming a part of commutator 1 consists of a piece of insulating material which breaks the circuit as it passes brush 5. The parts 2, 3 and 4 comprise a centrifugal-contactor; 2 shows a metallic hub, 4 a weight, connected together by a spring 3. The standard 10 supports an adjustable screw 11 forming a stationary contact. An electro-magnet 12 is connected to lines A¹ and A² through circuit C, C¹ and C² and operates feed-rod 15 by means of pawl 13 and ratchet-wheel, 14. An insulating base 16 secures motor 6, brush 5 and stationary contact 10 in place.

In carrying out my invention I preferably employ a motor of the commutator type shunt wound, the speed of which proves to be more sensitive to variation in voltage across the terminals of same. On the shaft 8 of the motor is fixedly attached an ordinary periodic circuit closer which makes and breaks the shunt circuit C, C¹ and C² producing an intermittent current as it passes conducting brush 5. On the same shaft a centrifugal-contactor comprising parts 2, 3 and 4 is fixedly attached and connects electrically to periodic circuit closer 1 through shaft 8. An adjusting screw 11 limits the distance between the points of contact when the motor is in operation, which determines the voltage across the arc. The electro-magnet herein shown in preferably of the ordinary type consisting of an iron core wound with wire which actuates the feed mechanism of lamp by means of the pawl and ratchet-wheel, the pawl comprising the armature of said electro-magnet.

This arrangement is particularly adapted to hand-feed arc-lamps, such as those now commonly used for moving picture machines, and has the advantage of remote control. The electro-magnet 12 and the feeding mechanism 13 and 14 is fixedly attached to the feed-rod of the arc-lamp, while the motor, periodic circuit closer, centrifugal-contactor and adjusting contact screw 15 can be located at any desired distance from the arc or placed in any position, which insures its protection from extreme heat and carbon dust which is a recognized menace to operating mechanism forming part of an arc-lamp.

The operation of this device will then be as follows: The carbons being connected to a proper source of supply by line wires A¹, A² through a rectifier, the line switch is then closed and the carbons brought in contact and separated by feed-rod 15 to establish the arc. On closing the line switch the motor immediately starts running, the speed of which will be in proportion to the voltage across the terminals of same, which in turn depends on the distance between the carbon points of the arc. If the carbon points are far apart the voltage of the feed circuit A¹ and A² raises which speeds up the motor, which in turn closes the circuit C, C¹ and C² through the centrifugal-contactor and completes the circuit through electro-magnet 12. When the motor is up to the speed that closes the centrifugal-contactor and the circuit is complete, the periodic circuit closer produces an intermittent current through the relay 12 which energizes the iron core of same and attracts the pawl 13, which in turn operates the feed-rod 15 by rotating ratchet-wheel 14, thus feeding the carbons until they are close enough for the voltage to drop across the terminals of the motor and lower the speed of same which simultaneously opens the centrifugal-contactor and electro-magnet 12 ceases to operate. When the consumption of the carbons is sufficient to raise the resistance of the arc which increases the voltage across same, the operation is repeated, thus, producing a constant voltage across the arc, which in turn increases the steadiness of the light from same. Any given voltage may be obtained across the arc by adjusting the distance between contact points of centrifugal-contactor, by means of adjusting screw 11.

55 While I have illustrated and described the preferred construction and arrangement of the various parts, it will be obvious from the foregoing description that the device is susceptible of considerable modification, without departing from the essential features or sacrificing any of the advantages thereof as come within the scope of the claims appended hereto.

Having thus fully described my invention,

what I claim as new and desire to secure by Letters Patent is—

1. In a carbon feeding mechanism, the combination of an arc circuit and an arc lamp connected thereto, an electric motor operating from the arc circuit and the speed of same varying with the voltage of said arc circuit, a periodic circuit closer and a centrifugal switch attached to the rotating member of said motor, and a circuit including a source of E. M. F. and said circuit closer and switch and means responsive to the intermittent closure of the circuit for feeding one of the electrodes toward the other.

2. In a carbon feeding mechanism, the combination of an arc circuit and an arc lamp connected thereto, an electric motor operating from the arc circuit and the speed of same varying with the voltage of said circuit, a periodic circuit closer and a centrifugal switch attached to the rotating member of said motor, a circuit including a source of E. M. F. and said circuit closer and switch and means responsive to the intermittent closure of the circuit for feeding one of the electrodes toward the other, and said centrifugal switch having means for adjusting contacts of same.

3. In a carbon feeding mechanism, the combination of an arc circuit and an arc lamp connected thereto, an electric motor operating from the arc circuit and the speed of same varying with the voltage of said circuit, a periodic circuit closer and a centrifugal switch attached to the rotating member of said motor, a circuit including a source of E. M. F. and said circuit closer and switch and means responsive to the intermittent closure of the circuit for feeding one of the electrodes toward the other, and one contact of said centrifugal switch being stationary.

4. In a carbon feeding mechanism, the combination of an arc circuit and an arc lamp connected thereto, an electric motor operating from the arc circuit and the speed of same varying with the voltage of said circuit, a periodic circuit closer and a centrifugal switch attached to the rotating member of said motor, a circuit including a source of E. M. F. and said circuit closer and switch and means responsive to the intermittent closure of the circuit for feeding one of the electrodes toward the other, one contact of said centrifugal switch being stationary, and said stationary contact of centrifugal switch having means for adjusting same.

5. In a carbon feeding mechanism, the combination of an arc circuit and an arc lamp connected thereto, an electric motor operating from the arc circuit and the speed of same varying with the voltage of said arc circuit, a periodic circuit closer and a cen-

trifugal switch attached to the rotating member of said motor, a circuit including a source of E. M. F. closing through said periodic circuit closer and centrifugal switch and connecting to an electro-magnet, and said electro-magnet operating a pawl and ratchet for actuating feeding gear.

In testimony whereof I have hereunto set my hand in presence of two subscribing witnesses.

WALTER G. PREDEY.
